UNITED STATES PATENT OFFICE

172,782

COMBINED LAMP DOOR AND LENS

Edward N. Cole and Clare M. MacKichan, Detroit, Mich., assignors to General Motors Corporation, Detroit, Mich., a corporation of Delaware

Application September 10, 1953, Serial No. 26,760

Term of patent 7 years

(Cl. D48—32)

To all whom it may concern:

Be it known that we, Edward N. Cole and Clare M. MacKichan, citizens of the United States, and residents of Detroit, Michigan, have invented a new, original, and ornamental Design for a Combined Lamp Door and Lens, of which the following is a specification, reference being made to the accompanying drawing, forming a part thereof.

In the drawing:

Figure 1 is a perspective view of a combined lamp door and lens, showing our new design.

Figure 2 is a side elevational view thereof.

Figure 3 is a sectional view on line 3—3 of Figure 4.

Figure 4 is a top elevational view of the device shown in Figure 1.

The dotted lines shown in the drawing are for illustrative purposes only.

We claim:

The ornamental design for a combined lamp door and lens, substantially as shown and described.
